KARL JOHAN GLANS AND JÖNS EMANUEL GLANS, OF STOCKHOLM, SWEDEN.

FIREARM.

Application filed February 26, 1926. Serial No. 90,716.

This invention relates to improvements in firearms and more particularly such firearms of the breech-loading class, as are used in contest shooting.

- 5 A firearm of this kind, in order to be placed in the highest class, must needs be of the very best quality of manufacture and provided with a firing and cocking mechanism very sensitive and easily movable.
- 10 The precision of the hit depends largely upon these circumstances, as the muscular strain of the shot is liable to influence unfavorably, in case the space of time increases.

In using firearms of the type in question 15 the pulling of the trigger takes place in two moments. The last moment, the so-called "quick pressure," consists in a very small movement of the trigger, the corresponding muscular movement of the hand being very 20 slight. Nevertheless it has not been possible to ensure sufficient precision of this moment, the cause being that the inertia of the firing-pin is too great, which will cause a certain space of time to pass before the 25 moment of the hitting of the cartridge.

According to this invention the inertia of the firing-pin is reduced to a minimum and the firing-pin is in contact with the cartridge before the firing takes place. The period 30 of time elapsing between the action on the trigger and the firing, will be the smallest possible and the muscular movements of the hand will not have time to affect the precision of the hit. The firing-pin by means 35 of a resistance is prevented from hitting the cartridge, and the resistance is eliminated before the moment of firing.

Loading is facilitated by swinging the finger-lever downwardly, which operation 40 carries down the breech-block, at the same time preventing the raising of the hammer, the hammer raising element being forced-guided in one side of the back frame.

The invention is fully disclosed in the following specification, of which the accompanying drawing forms a part, in which the separate parts of our invention are designated by reference figures in each of the views, and in which—

50 Figure 1 is a vertical longitudinal section through the mechanism of the firearm. Fig. 2 is a plan section on line II—II, Fig. 1, and Fig. 3 a cross section on line III—III, Fig. 1. In Fig. 1 the finger-lever, in its 55 swung-out position, is shown by dot-and-dash lines. Fig. 4 shows the breech-block

drawn to a reduced scale. Figures 5 and 6 show details.

The barrel 2 is screwed into the front part of the back frame or receiver 1, to the rear part of which the butt-stock 3 is secured in the usual manner. In receiver 1, the breech-block 4 is vertically movable, guided by the side walls of a vertical opening in the receiver. The upward movement of block 4 60 is limited by means of an outstanding member 5 which abuts against the top side of a corresponding recess in the receiver. The upper part of the breech-block is provided with a semicircular recess 6 for the cartridge, 65 which is inserted through a hole 7 in the rear wall of the receiver, when the breech-block is lowered down to its loading position, in which position the bottom of recess 6 is in alignment with the bottom of hole 7. When 70 inserted, the cartridge 9 bears against the surface 10 of the breech-block, the firing-pin 11 being in position at said surface. The firing-pin is characterized by its particularly light weight, this being made possible by combining the firing-pin with a shaft 12, connected to the firing-pin by means of two flanges 11¹ located in corresponding recesses 12¹ and 12² in said shaft. Between said recesses there is an inside 75 flange 12³ corresponding to the neck 11² of the firing-pin. The axial length of said neck 11² is slightly greater than the width of flange 12³, giving the firing-pin a small clearance in the recess 12² of the shaft between flange 11¹ and flange 12³, as shown in 80 Figures 1 and 2, this permitting the firing-pin to have a slight movement with relation to the shaft. In the position of the members shown in these figures the operation 85 of discharging the firearm is supposed to have been performed and the firing-pin is on the point of penetrating into the cartridge, which penetrating operation transfers the clearance from the back to the 90 front side of flange 12³. The recesses of the shaft are open to one side in order to facilitate the insertion of the firing-pin. Moreover, the shaft is provided with a slot for the hammer 13 of the firearm and for the 95 upper arm 15 of the set-trigger 14, said arm 15 being located between two pins 12⁴, 12⁵ in the shaft serving for engagement by the arm 15. The shaft is movable in a hole in the breech-block, said hole being closed by 100 means of a removable screw-plug 16. The breech-block 4 is provided with suitable re-

cesses for the operative parts of the firing mechanism. The hammer 13 is pivoted on a pin 17 and provided with an arm 18 abutting against the trigger-arm 19, which is made in one piece with trigger 20. The trigger is pivoted on a pin 21 and provided with an adjusting set-screw 22 bearing against the trigger spring 23. An adjustable stop is located in front of the trigger, 10 said stop constituting an eccentric 24, the object of which is to vary the stroke of the stroke of the trigger by turning the eccentric at different angles. The hammer spring 25 acts upon arm 18. The set-trigger 14 turns on a pin 26 and is actuated in the direction of the barrel by means of springs 27 and 28.

In finger-lever 29 the set-trigger by means of a set screw 30 is locked in such a position 20 that arm 15 abuts against the forward pin 12⁴, and consequently shaft 12 holds the firing pin 11 in position against the cartridge. A spring 28 connected to a piston 31, the stroke of which is limited by the action of a 25 pin 32 against a plate 33, coacts with a rod 34, guided in breech-block 4 and connected to set-trigger 14. Said rod 34 also penetrates the rear wall of receptacle 1, thus locking the breech-block in its upper position. The 30 finger-lever 29 by means of a pin 35, extending through a vertically oblong hole, is connected to the breech block, at the same time being connected to receptacle 1 by means of a pin 36 extending through a horizontally 35 oblong hole. Lever 29 is held in position by means of a spring-actuated bolt catch 37. To facilitate the loading operation, the finger-lever is swung down to the position shown in dot-and-dash lines, the first part 40 of this swinging movement taking place without moving the breech-block until the set-trigger 14 is set free. Then rod 34 is forced out of catch with the receptacle. During the continued swinging motion of 45 the finger-lever the breech-block follows, until it has reached its opening position, when the surfaces 4¹ abut against the finger-lever. During this movement the spring-actuated extractor 38 is brought into 50 function. Said extractor 38 is located in a groove in the side-wall of receptacle 1 and executes a swinging movement between the point of a screw 39 and a projection 40 resting against the side of the breech-block. A 55 vertical groove 41 is arranged in the breech-block for a projection 42 of the extractor, said groove at the top having a bent portion, as shown in Fig. 4 and besides being wedge-shaped, as shown in Fig. 3. By this arrangement, the extractor during the opening operation will move backwardly and will at the same time execute a swinging movement, all with the object of extracting the cartridge shell. Suitable recesses 43 in 60 the breech-block facilitate these movements.

The raising of the hammer is caused by the eccentric 44, formed on a pin 45 turning in the side wall of the breech-block and co-acting by means of a cam 46 with a groove in the turning head 47, which head turns 70 in the side wall of receptacle 1 and is provided with a turning-lever 48. A spiral spring 49 is secured at one end to the receptacle and at the other end to lever 48 in order to force the lever back to its normal 75 position after the raising of the hammer. During the opening movement of the breech-block, cam 46 slides into a groove 50 in the receptacle wall, said groove being located exactly below the groove of turning head 47. 80 During the closing movement the set-trigger 14 is carried into such position that its lower end overlies the set screw 30, and at the same time shaft 12 by means of springs 27, 28 is pressed against the screw plug 16. 85 By this means the firing-pin is secured from action, said springs being powerful enough to take up the blow of the hammer, and the right hand flange 11¹ being in contact with the flange 12³ of shaft 12. The movement 90 of set-trigger 14 so as to carry its extreme lower end into abutting relation with the end of screw 30, as shown in Fig. 1, is accomplished by applying a slight pressure on the set-trigger the firing-pin 11 abutting 95 against the cartridge with a certain degree of pressure, caused by the spring action of the set-trigger arm 14.

Within the range of the invention, the details specified above may be varied as to 100 material, shape and arrangement.

Having fully described our invention, what we claim as new and desire to secure by Letters Patent, is:—

1. In a breech-loading firearm, the combination of a firing-pin, a firing mechanism co-acting with said firing-pin, and a setting device adapted to act upon said firing-pin so that the firing-pin is held under pressure against a cartridge carried by the firearm 105 when the firing mechanism is in its firing position.

2. In a breech-loading firearm, the combination of a firing-pin, a firing mechanism co-acting with said firing-pin, and a setting 115 device adapted to act upon said firing-pin so that the firing-pin is held under pressure against a cartridge carried by the firearm when the firing mechanism is in its firing position, said firing mechanism including a 120 slide shaft for operating said firing-pin, said pin and shaft having co-operating means for connecting them together and permitting relative movement in the firing direction sufficient to cause the firing-pin to 125 penetrate the cartridge.

In testimony whereof we have signed our names to this specification.

KARL JOHAN GLANS.
